SELF-LATCHING HANDLE
Benjamin M. Saunders, 1701 Lydia Drive NW,
Huntsville, Ala.
Filed July 31, 1963, Ser. No. 299,124
7 Claims. (Cl. 16—126)
(Granted under Title 35, U.S. Code (1952), sec. 266)

The invention described herein may be manufactured and used by or for the Government of the United States of America for governmental purposes without the payment of any royalties thereon or therefor.

This invention relates to a latching means for panels, doors, drawers, and the like and more particular to a handle which includes a built-in mechanism for locking the panel, door, or drawer in position.

In large electronic chassis constructions, drawers carrying electronic components are fitted into spaces in a cabinet so they may be easily pulled out from the cabinet to reveal the electronic components for repair, replacement, or inspection purposes. The drawers usually have a face panel which abuts the cabinet surface about the cabinet opening when the drawer is fully inserted into the cabinet. Also, such electronic chassis constructions are often fitted with panels or doors which cover cabinet openings and abuts the cabinet surface about the opening to provide easy access to the electronic gear within the chassis when desired.

Heretofore, these panels and drawers have usually been secured to the cabinet by conventional screw and nut arrangements. Thus, considerable time was entailed to remove or secure the cabinet's panels and drawers and often the nut or perhaps the screw would be accidentally dropped into the electrical equipment to cause electrical shorts.

Other mechanical means were utilized, occasionally, to hold the panel or drawer to the cabinet, but they usually held only at one point per panel side. Thus, a simplified means for securely holding a panel or a drawer to a cabinet which also provided for an easy manner to remove the panel or drawer has existed for a long period of time.

Accordingly, it is an object of the present invention to provide a latching mechanism for panels and drawer face panels to securely hold the panels and drawer face panels to the cabinet and yet still provide for easy removability.

Another object is to provide a combined handle and latching means for panels, drawers, and the like, which is simple in design and trouble-free in operation.

Other and further objects, uses, and advantages of the present invention will become apparent as the description proceeds.

The invention is drawn to a channel-shape handle having its two end portions substantially perpendicular to its middle portion. The two end portions extend through elongated slots adjacent a side edge of a panel or drawer face panel and each end portion is pivotally secured to a structural member which projects from the backside of the panel.

Adjacent each pivoted end of the handle is a ramp latch for engaging the inner corner of the cabinet edge which defines the cabinet opening. A spring extends between the structural member attached to the backside of the panel and each handle end portion to bias the handle toward the cabinet edge forming the opening. The ramp latch extends behind the face of the cabinet and, thus, prevents the panel from being removed. No modification or attachments need be made to the cabinet.

When the handle is pivoted toward the panel's center, the ramp latch is pivoted away from cabinet's edge so that by pulling back on the handle the panel will be removed from the cabinet to reveal the opening.

2

It is apparent that by utilizing two such handles, a panel or drawer face panel is securely fastened to the cabinet by locking action of the ramp latch and also easily released by manually pivoting the handles toward the panel center at the same time.

This will be more readily understood by the following detailed description when taken together with the accompanying drawings in which:

FIGURE 1 is a perspective view of a panel having two latching handles of the present invention installed thereon.

FIGURE 2 is a detailed perspective view of one of the latching handles shown in FIGURE 1, portions of the panel removed for clarity.

FIGURE 3 is a perspective view showing the latching handles of the present invention installed on the face panel of a drawer of a cabinet.

FIGURE 4 is an elevational cross-sectional view showing the panel of FIGURE 1 installed within the opening of a cabinet, with phantom lines indicating the unlatched position of the handles.

Referring now to FIGURE 1 which shows a rectangular cabinet panel 11 having two self-latching handles 13 of the present invention mounted thereon adjacent two opposed side edges. The handle 13 as shown is channel shaped and comprises two identical end portions 15 substantially perpendicular to its middle portion 17. Each end portion 15 extends through one elongated slot 19 of a pair of elongated slots aligned and evenly spaced from a side edge of the panel 11.

As shown best in FIGURES 2 and 4, each handle end portion 15 is slotted or bifurcated to pivotally receive a connecting lug 21 at its extremity. A dowel pin 23 pivotally secures the bifurcated portion of the handle end portion 15 to the lug 21.

The lug 21 is supported by a rib 25 which projects from the backside of the panel 11. The lug 25 has a threaded bolt member 27 projecting from its base through a hole in the rib 25 by which a nut 30 securely tightens the lug 21 to the rib 25.

A ramp latch 29 is also positioned between the bifurcated parts of the handle 13 and is securely held therein by a pair of fasteners 31. The ramp latch 29 slopes from the outer surface of the bifurcated portion of the handle 13 into an inside corner 33 defining an obtuse angle. The bottom surface 35 of the inside corner having a sloping characteristic to prevent the corner from jamming against the cabinet edge 37 (FIGURE 4) of the cabinet 38 when the handles 13 are pivoted as described hereinafter.

A leaf spring 39 has a flat portion 41 extending between the base of the lug 21 and rib 25 as shown in FIGURES 2 and 4. The lug bolt extends through the flat portion 41 to securely anchor the spring 39 in position. The spring 39 extends outwardly from the rib 25 and its flat portion 41 and contacts the handle end portion 15. Thus, it is apparent the spring 39 will bias the handle 13 outwardly in a pivoting movement about the dowel pin 23.

The slots 19 within the panel are elongated to permit a slight rotation of the handle 13 about its pivot. This elongation is such that the handle 13 may pivot inwardly toward the panel center at an angle at least equal to the angle the sloping surface 43 of the ramp latch 29 makes with the center line of the handle end portion 15. This arc angle in most applications will range from 7 to 15 degrees.

The handles 13 are shown mounted on the face panel 51 of a drawer 53 for a cabinet 57 in FIGURE 3. In this embodiment the sides 55 of the drawer 53 serve the same purpose as the ribs 25 of FIGURE 1.

In operation, an individual will grasp each handle 13 and pivot them toward the panel center, as shown by the phantom lines of FIGURE 4, so that the ramp

latches 29 will be removed from the cabinet edge 37 forming the opening 43. The outer surface of the ramp latch 43 will be substantially parallel and spaced from the cabinet edge 37 when the handle 13 is pivoted to its maximum extent toward the center of the panel. Then 5 by pulling the handles 13 away from the cabinet, the panel 11 will be removed from the opening 43. Thus, it is apparent that by the use of two handles 13 adjacent opposed edges of the panel 11, an individual may apply pivoting forces on the handles 13, such that the force on one handle 13 will have a direction opposite to the force on the other, and the panel 11 will have no resultant force causing a pivoting or sidewise movement of the panel 11 itself.

In positioning the panel 11 over the opening, the handles 13 are once again grasped and pivoted toward the center the arc distance permitted by the elongated slots 19, and the panel 11 is moved over the opening 43 with the projecting ribs 25 (or drawer sides, bottom, or top), extending into the cabinet opening 43. The panel 11 is 20 located so its backside adjacent its edges will abut the face surface of the cabinet 38.

The handle 13 may then be released and the spring 39 will force the inside corner 33 of the latch ramp 29 into reception of the inner edge corner of the cabinet edge 25 37. The bottom surface 35 of the inside corner 33 portion of the latch 29 will thus extend behind the face of the cabinet 38 and securely lock the panel 11 in position.

Thus, it is apparent that a novel self-latching hardware has been disclosed for panels, drawers, and the like which combines a one-piece channel shape or bale handle with a latch mechanism of remarkable simplicity. By providing a slight inward pressure on the handle so as to pivot it approximately 7 to 15 degrees, the locking or latching mechanism is released and the panel may 35 easily be removed.

Obviously, many modifications and variations of the present invention are possible in the light of the above teachings. It is, therefore, to be understood that within the scope of the appended claims the invention may be 40 practiced other than as specifically described.

What is claimed is:

1. In a panel adapted to cover a cabinet opening, the improvement, comprising:

- (a) a handle having a bifurcated end portion;
- (b) a connecting lug pivotally received within said bifurcated end portion adjacent its extremity;
- (c) means for fixedly securing said connecting lug to said panel;
- (d) a ramp latch partly positioned within said bifurcated end portion and fixed thereto;
- (e) said ramp latch having a side surface sloping outwardly from the outer surface of the bifurcated end portion into an inside corner defining an obtuse angle, said inside corner being adapted to receive the inner edge corner of the cabinet opening;
- (f) said sloping edge surface defining an angle with the center line of the bifurcated end portion of 7 to 15 degrees;
- (g) said inside corner having a sloping characteristic 60 for its bottom surface to prevent jamming against the cabinet edge when the handle is pivoted about said connecting lug.

2. The improvement defined by claim 1, including:

- (a) a spring means for pivotally biasing said handle toward the cabinet edge opening so as to place the bottom edge surface of said inside corner portion of the ramp latch behind the face surface of the cabinet; and
- (b) means for limiting the pivoting of said handle to 70 an arc angle at least equal to the angle the sloping edge surface of said ramp latch makes with the center line of said handle.

3. In a panel adapted to cover a cabinet opening, the improvement, comprising:

- (a) a bail handle having two substantially parallel end portions;
- (b) each end portion having a latch fixed thereto;
- (c) each said latch having a side surface extending from the end portion into an inside corner defining an obtuse angle, said inside corner being adapted to receive the inner edge corner of the cabinet opening;
- (d) means for pivotally securing the extremity of each said end portion to the backside of said panel;
- (e) a spring means for pivotally biasing said handle toward the cabinet edge opening so as to place the bottom edge surface of said inside corner portion of each said latch behind the face surface of the cabinet; and
- (f) means for limiting the pivoting of said handle.

4. In a panel adapted to cover a cabinet opening, the improvement, comprising:

- (a) a pair of bail handles, each handle having two substantially parallel end portions extending from its middle portion;
- (b) each end portion of said handles having a ramp latch fixed thereto;
- (c) each said ramp latch having a surface extending outwardly from the outer surface of the end portion into an inside corner, said inside corner being adapted to receive the inner edge corner of the cabinet opening;
- (d) means for pivotally securing each said end portions to the backside of said panel;
- (e) a spring means for pivotally biasing each said handle toward the cabinet edge opening so as to place the bottom edge surface of said inside portion of the ramp latch behind the face surface of the cabinet;
- (f) said handles being spaced apart and located so each may be manually grasped at the same time and pivoted by manually applied forces having a direction opposite to each other.

5. In a panel adapted to cover a cabinet opening, the improvement, comprising:

- (a) a rib extending from the backside of said panel;
- (b) a bail handle having two substantially parallel end portions extending from its middle portion;
- (c) said panel having a pair of elongated slots adjacent and evenly spaced from a side edge thereof;
- (d) said handle having its end portions extending through said pair of slots, one end portion extending through one slot;
- (e) a pair of connecting lugs, each lug pivotally attached at one end to the extremity of one of said handle end portions and fixedly attached at its other end to said rib;
- (f) each handle end portion having a latch with a side surface defining an inside corner portion which is adapted to receive an outside corner portion of the cabinet edge forming the cabinet opening; and
- (g) spring means for pivotally biasing said handle toward the cabinet edge opening.

6. A self-latching handle for a panel, comprising:

- (a) a channel shaped member having two end portions substantially perpendicular to its middle portion;
- (b) a pair of connecting lugs;
- (c) each said end portion being slotted at its extremity;
- (d) one of said connecting lugs being pivotally received within one of said slotted end portions and the other of said connecting lugs being pivotally received within the other of said slotted end portions;
- (e) a pair of ramp latches;
- (f) one of said ramp latches being partly positioned within one of said slotted end portions and the other of said ramp latches being partly positioned within the other of said slotted end portions;
- (g) each said ramp latch having a side surface slop-

ing from the outer surface of a slotted end portion into an inside corner defining an obtuse angle; and
(h) spring means for pivotally biasing said handle.

7. A self-latching handle for a panel, comprising:

- (a) a bail handle having two substantially parallel end portions;
- (b) each said end portion having a latch fixed thereto;
- (c) each said latch having a side surface extending from the end portion into an inside corner defining an obtuse angle;
- (d) each said end portion having a connecting lug pivotally attached thereto; and

5

(e) spring means for pivotally biasing each said end portion.
